(57) **CLAIM**

The ornamental design for pan handle, as shown and described.

DESCRIPTION

FIGS. 3.1-4.7: Pan handle

FIG. 3.1 is a top plan view of a pan handle of the claimed design according to one embodiment;

FIG. 3.2 is a perspective view of the pan handle shown in FIG. 3.1;

FIG. 3.3 is a back elevational view of the pan handle shown in FIG. 3.1;

FIG. 3.4 is a left elevational view of the pan handle shown in FIG. 3.1;

FIG. 3.5 is a right elevational view of the pan handle shown in FIG. 3.1;

FIG. 3.6 is a bottom plan view of the pan handle shown in FIG. 3.1;

FIG. 4.1 is a perspective view of a pan handle of the claimed design according to another embodiment;

FIG. 4.2 is a front elevational view of the pan handle shown in FIG. 4.1;

FIG. 4.3 is a top plan view of the pan handle shown in FIG. 4.1;

FIG. 4.4 is a back elevational view of the pan handle shown in FIG. 4.1;

FIG. 4.5 is a right elevational view of the pan handle shown in FIG. 4.1;

FIG. 4.6 is a left elevational view of the pan handle shown in FIG. 4.1; and

FIG. 4.7 is a bottom plan view of the pan handle shown in FIG. 4.1.

The broken line showing of a pan is included for the purpose of illustrating environment and forms no part of the claimed design.

1 Claim, 13 Drawing Sheets
